UNITED STATES PATENT OFFICE.

GEORGE M. HUBBARD, OF NEW HAVEN, CONNECTICUT, ASSIGNOR TO
W. & E. T. FITCH, OF SAME PLACE.

DESIGN FOR A CLASP FOR BELTS.

SPECIFICATION forming part of Design No. 21,064, dated September 22, 1891.

Application filed August 31, 1891. Serial No. 404,346. Term of patent 7 years.

To all whom it may concern:

Be it known that I, GEORGE M. HUBBARD, of New Haven, in the county of New Haven and State of Connecticut, have invented a new Design for a Clasp for Belts, (Case U); and I do hereby declare the following, when taken in connection with accompanying drawings and the letters of reference marked thereon, to be a full, clear, and exact description of the same, and which said drawings constitute part of this specification, and represent, in—

Figure 1, a face view of the two parts connected; Fig. 2, a face view of the eye portion of the clasp detached; Fig. 3, a face view of the hook portion of the clasp detached.

This invention relates to a design for a clasp for securing a belt around the body; and the design consists in the configuration and ornamentation as shown in the accompanying illustrations.

A represents the loop of the eye portion, and B the loop of the hook portion. One side

a of the eye-loop B represents a cord, and from this side is the representation of eyes b b, as upon the end of posts c c. Between the top of the posts is the representation of a cord d, the cord represented as extended over the posts and as forming braces e e. The hook portion b is the same as the eye portion, except that the posts are represented as terminating in hooks f instead of eyes, and, as represented in Fig. 3, the design representing a tennis-net.

I claim—

The design for a clasp for belts, as described, and shown in the accompanying illustrations.

In testimony whereof I have signed this specification in the presence of two subscribing witnesses.

GEORGE M. HUBBARD.

Witnesses:

LILLIAN D. KELSEY,
FRED C. EARLE.
